UNITED STATES PATENT OFFICE.

JOSEPH W. ROSCHE, OF MINNEAPOLIS, MINNESOTA.

FLUID-CLUTCH.

1,041,169.

Specification of Letters Patent. Patented Oct. 15, 1912.

Application filed March 26, 1910. Serial No. 551,712.

To all whom it may concern:

Be it known that I, JOSEPH W. ROSCHE, a citizen of the United States, residing at Minneapolis, in the county of Hennepin and State of Minnesota, have invented a new and useful Improvement in Fluid-Clutches, of which the following is a specification.

My invention relates to improvements in liquid clutches and my object is to render the control of power transmitters more complete and flexible, and to secure this by a mechanism which shall give neither shock nor jar to connected machinery, and shall be simple in manipulation and completely self lubricating. To secure these results I use a radial system of pistons connected to a single crank and operating in cylinders fixed in a shell to which rotary power is applied. The transmitting medium is a suitable fluid contained within the shell and supplied to the cylinders by suitable valves and passageways. These devices as I have used them are illustrated in the accompanying drawings which constitute part of my specification.

In said drawings Figure 1 illustrates the application of my invention; Fig. 2 is an elevation of my invention; Fig. 3 is a plan view of the same; Fig. 4 is a transverse section on line A—A of Fig. 3, the shaft, crank and system of pistons being omitted to simplify the view; Fig. 5 is a section on line B—B of Fig. 2, the cranks and system of pistons being omitted to simplify the view; Fig. 6 is an elevation of the transmitter illustrating the positions of the different pistons at one position of the crank, a portion of the cover being removed; Fig. 7 is a partial cross section on line C—C of Fig. 6, the valves, shaft, crank and pistons being left in full; Fig. 8 is a section on line D—D of Fig. 6; and Figs. 9 and 10 are sections of details showing the check valves and their cages.

Similar numerals in the different figures refer to identical parts.

In the drawings 2 represents a cylindrical shell or housing closed on one end by the disk plate 3 which makes a fluid tight joint with it. The shell is formed with a plurality of inwardly projecting cylinders 4 which are integral and longitudinally tangent to a circle about the center or axis of the shell. A shaft 5 enters the inner end of this shell upon its axis through a stuffing box 6 and throttle pins 7 arranged in a circle and equally spaced apart, enter through the

stuffing boxes 8. Within the shell near its inner end is an annular pressure reservoir chamber 9 connecting to a chamber 10 adjoining the plate 3 through radial recesses 11 lying between the chamber 9 and shaft 5. The reservoir chamber 10 also connects with the chamber 9 through circumferential slots 12 forming ingress ports from the chamber 10 into the outer end of each cylinder for fluid. An egress port 14 for each cylinder adjoins the ingress port thereof and connects with chamber 9. Interposed between each pair of ports 12 and 14 is an automatic check valve 13 which permits ingress of fluid into the cylinder with which said ports are associated and prevents egress of said fluid back into the chamber 10. There is also an automatic check valve 15 in each port 14 which is closed to fluid in the chamber 9 and prevents the fluid forcing back from chamber 9 into the connected cylinder.

Pistons 17 in the cylinders are connected by links 18 to a pitman wheel 19 which is free to revolve on the wrist of a double crank 20 in such a manner that during each revolution of the crank 20 with relation to the shell 2, the pistons 17 perform one complete reciprocation within the cylinders 4. The links 18 are connected with the pitman wheel 19 at equal distances from the axis of the wrist of the crank 20. The links 18 are formed with their pitman ends designed to engage a succeeding link in the retracted position of the piston and lock the pitman 90 from revolution in the casing 2 to produce extension of a preceding piston. The position of the links 18 on the pitman wheel is substantially tangential to the circle about the axis of the crank wrist through the 95 points of connection of the links 18 and lie on the axis of the cylinder. This method of connecting the links 18 permits the reciprocation of the pistons in the cylinders 4 with equal oscillation of the links on the two sides 100 of the axis of the cylinders during their working stroke. The connection of all the pistons with the pitman wheel in their different positions of reciprocation imparts the different stresses in the different pistons to 105 the pitman wheel simultaneously and the resulting stress is transmitted to the pitman wheel by the crank 20 equalizing the action of the pistons. The crank 20 is carried by the shaft 5 which has bearings in the shell 2 110 and the plate 3 and is free to revolve therein.

The check valves 13 are closed to fluid in

slots 14 and rest on valve seats 21 in cages 22, which have slots or ports 23 corresponding with ports 12 of shell 2, and which are threaded into said shell in such a manner as to be removable through the openings in the shell 2 closed by plugs 24. Each valve 13 has a stem 25 sliding in a sleeve 26 on the corresponding cage. The motion of valves 13 is limited by pins 27 passing through the stems and into slots 28 in said sleeves.

10 The check valves 15 are closed to fluid in chamber 9 and rest on valve seats 29 on cages 30, said cages being formed with openings 31 corresponding with slots 14. The cages 30 are threaded into the shell 2 in such a manner as to be removable through the openings closed by the plugs 32. Each valve 15 is formed with a stem 33 which slides in a sleeve 34 on the corresponding cage. The motion of valves 15 is limited by pins 35 carried by the stems 33 and sliding in slots 36 in said sleeves.

Between chamber 9 and the radial recesses 11 are mechanically operated throttle valves 25 37 which have valve stems 38 operating in guide sleeves 39. These guide sleeves have heads 40 which are threaded into shell 2 in such a manner as to be removable through the openings closed by the plugs 41. The 30 action of valves 37 is controlled by throttle pins 7 which have a diagonal guide slot 42 engaging pin 43 on the stem 44 of valves 37 in such a manner that the longitudinal motion of the pins 7 causes pins 43 to traverse slots 42 and forces valves 37 to open. The 35 closing of said valves may be effected by reversing the motion of said pins or by fluid pressure against said valves. Throttle pins 7 are operated as shown in Figs. 1 and 3, by 40 means of a controlling collar 45 which slides on shaft 5, the action of said collar being secured by a suitable lever 46. Integral with the plate 3 is a truncated cone 47 through which power may be applied to the 45 shell 2 by a cone clutch 48.

In operation my device is located between the driving and driven elements. Shaft 5 for example being continuous with the drive shaft of some machine such as an automobile 50 the speed of which is to be changeable, while the power is applied to shell 2 by a cone clutch 48 engaging with cone 47 on plate 3 or by other equivalent means. All cavities in shell 2 being filled with oil or other suitable fluid, the application of rotary power to said shell revolves it and tends to cause the pistons 17 to move within the cylinders 4 with a reciprocating motion. As each piston 55 is being withdrawn from its cylinder it tends to draw oil through its valve 13 from the reservoir chamber 10 and during the remainder of the stroke closes valve 13 and tends to force this oil through valve 15 into the annular chamber 9. It is evident that 60 the oil thus pumped into chamber 9 by all

the pistons can return to reservoir 10 through recesses 11 and so complete its circuit of flow, only if valves 37 are open. If valves 37 are closed, however, oil can not pass from chamber 9 to reservoir 10, the circulation of oil is blocked, and as all the cavities of the shell are at all times full of oil, the action of the pistons in their cylinders is blocked. This stops the rotation of crank 20 and shaft 5 with relation to shell 2, and shaft 5 and shell 2 must revolve together thus transmitting the full speed and power of the power clutch to the drive shaft. When the valves 37 are open sufficiently to allow all the oil pumped by the pistons to return freely from the chamber 9 to reservoir 10, the relative motion between shaft 5 and shell 2 will be a maximum and shaft 5 will be stationary or nearly so. Within the limits of relative motion, between shaft 5 and shell 2 produced by the open and closed positions of valves 37, any desired relative motion can be secured by partially opening valves 37 thus taking from the power shaft revolving at any uniform speed, any desired speed for the drive shaft of the machine.

In accordance with the patent statutes I have described the principles of operation of my invention together with the apparatus which I now consider to represent the best embodiment thereof but I desire to have it understood that the construction shown is only illustrative and that the invention can be carried out by other means and applied to uses other than those above set forth within the scope of the following claims.

Having described my invention, what I claim as new and desire to protect by Letters Patent is:—

1. In a fluid clutch, a rotatable casing and a crank shaft journaled in said casing, a plurality of cylinders mounted on said casing, pistons reciprocating in said cylinders, a pitman wheel freely journaled on the crank of said shaft, links pivotally mounted on said wheel successively about its perimeter in the same plane and connected with said pistons to operate the latter, said links being so formed as to engage each other successively during the rotation of the crank in the casing and prevent the rotation of said wheel in said casing.

2. In a fluid clutch, a rotatable casing and a crank shaft journaled therein, a plurality of cylinders mounted on said casing, pistons mounted on said shaft and operable in said cylinders, said cylinders having inlet passages communicating with a reservoir chamber in said casing near its periphery and outlet passages communicating with an annular pressure chamber in said casing, said pressure chamber communicating with said reservoir chamber through a passageway, and a control valve in said passageway adapted to control the flow of liquid from

said plurality of cylinders through said chamber, whereby in operation liquid is supplied to said cylinder inlets through the revolution of said casing and the speed of 5 said plurality of pistons in the cylinders is regulated by said control valve.

3. In a device of the class set forth, a cylindrical casing having a liquid reservoir and an annular pressure chamber communicating therewith by a valved passageway, a crank shaft journaled to revolve in said casing, a plurality of cylinders mounted on said casing tangential to a circle about said shaft having valved inlets from said reservoir at the periphery thereof and valve outlets to said pressure chamber adapted to receive liquid from said cylinders, pistons operating in said cylinders to draw liquid from said reservoir and force it into said annular 10 chamber, a pitman wheel journaled freely on said crank shaft and connected with said pistons to operate them and equalize the pressure thereon and a control valve between said pressure chamber and reservoir 15 adapted to regulate the flow of liquid from said piston, the connection between said pit-

man and piston being axial of said cylinder midway of the working stroke of said piston, whereby the action of said pistons is equalized and regulated. 30

4. In a device of the class set forth, a cylindrical casing having a plurality of piston cylinders, their axes being tangential to a circle about the axis of said cylinder, a crank shaft journaled on the axis of said casing and having a crank pin, pistons reciprocating in said cylinders and a pitman wheel freely journaled on said crank pin and links pivoted to the periphery of said pitman wheel and to said pistons to operate 35 the same, whereby a plurality of pistons may be operated in the same casing by links positioned substantially upon the axes of said cylinders. 40

In testimony whereof, I have signed my name to this specification; in the presence of two subscribing witnesses. 45
